CLAIM

The ornamental design for a garment liner, as shown and described.

DESCRIPTION

FIG. 1 is a front elevation of a garment liner, the rear elevation being a mirror image thereof;
FIG. 2 is a left side elevation of the garment liner of FIG. 1, the right side elevation being a mirror image thereof;
FIG. 3 is a top plan of the garment liner of FIG. 1; and,
FIG. 4 is a bottom plan of the garment liner of FIG. 1.
